UNITED STATES PATENT OFFICE.

FREDERICK WENING, OF CLEVELAND, OHIO.

SHADE HOLDER.

Application filed June 25, 1927. Serial No. 201,340.

This invention relates to improvements in that class of devices which are designed to support the one-piece glass globes or shades which are at the present time so largely in use for lighting purposes.

The general object of the present invention is the provision of an improved shade or globe holder which comprises a minimum number of easily and inexpensively formed parts capable of simple and ready assembly and withal, a holder which is neat and attractive in appearance and efficient and satisfactory in use.

Further objects of the invention are in part obvious and in part will appear more in detail hereinafter.

In the drawings, Fig. 1 is a side elevation of my improved holder with a globe supported thereby, part of said holder being broken away and in section for clearness of illustration; Fig. 2 is a bottom plan view of the holder, a part thereof being in section on the line 2—2, Fig. 1; Fig. 3 is a detail elevation thereof with a portion in section on the line 3—3, Fig. 2; Fig. 4 is a perspective view of the actuating lever for one of the globe supporting devices of the holder; Fig. 5 is a view similar to Fig. 3 and illustrating a slightly modified holder; Fig. 6 is a perspective view of the actuating lever used in Fig. 5; Fig. 7 is an elevation of a part of the skirt portion of the holder of Figs. 5 and 6 and showing the slot through which extends the actuating lever for one of the supporting devices of said holder; and Fig. 8 is a side elevation of said actuating lever.

The shade or globe holder illustrated in the drawings includes a canopy or bell-shaped body member 1 provided at its top with a short cylindrical portion 2 having openings to receive the inwardly bent ends 3 of a substantially U-shaped supporting wire 4. At its bottom, said body member is provided with an outwardly extending annular portion 5 merging at its outer end into a depending, cylindrical skirt portion 6 which terminates at its lower end in an annular bead 7.

In the embodiment of the invention here shown, said body member is provided with three supporting devices for the globe or shade 9, said devices being circumferentially

spaced about the inner surface of the skirt portion 6 of said member and being adapted for resilient engagement with the neck portion 10 of the globe or shade.

Two of said supporting devices are identical, being in the form of resilient fingers 12 made from metal strips. Each of said fingers includes a top portion 14, a depending body portion 15 and an inwardly and upwardly curved globe-engaging portion 16. The top portions of said fingers are adapted to be riveted or otherwise suitably secured to the bottom surface of the annular portion 5 of the body member 1; the depending body portions of said fingers are adapted to engage the inner surface of the depending skirt portion 6 of said member; and the curved lower end portions of said fingers are adapted to engage the outer surface of the correspondingly curved globe neck portion 10, all as clearly shown in Fig. 1. Preferably, and as shown, the skirt portion 6 of member 1 extends below said fingers so as to conceal them.

The third globe supporting device of the body member 1 is arranged in opposed relation to the other two devices, to-wit, the resilient fingers 12, as best shown in Fig. 2. Said third device includes a supporting member 18 in the form of a resilient metal strip, arranged circumferentially of the skirt portion 6 of said body member and having one of its end portions riveted or otherwise suitably secured to the inner surface of said skirt portion. The free end portion 19 of said resilient metal strip is adapted to normally lie alongside the inner surface of the skirt portion 6, as indicated in dotted lines, Fig. 2, in which position it is free of supporting engagement with the neck portion of the globe or shade 9, also indicated in dotted lines in said view.

The means for moving inwardly into globe-engaging position the free end portion 19 of member 18 comprises a lever extending through a transverse slot 21 in the skirt portion 6 of the body member 1. Said lever includes a head end portion 22 and an operating handle portion 23 bent at an angle thereto slightly greater than ninety degrees. The head end portion of said lever is adapted to lie within the skirt portion 6 and to engage at all times the resilient supporting

member 18, while the operating handle portion of said lever is adapted to lie outside said skirt portion. Preferably, and as shown, said handle portion is curved slightly to conform to the curvature of the skirt portion 6, so that when said lever is in its full line position, Fig. 2, the handle portion thereof will closely hug the outer surface of said skirt portion, this being the position 10 of said handle portion when the holder is supporting a globe or shade.

When the resilient supporting member 18 and its operating lever are in their dotted line positions, Fig. 2, the neck portion 10 of the shade or globe 9 may be readily inserted into and removed from the space within the skirt portion 6 of the body member 1, engagement and disengagement of the globe neck portion with the two resilient 15 fingers 12 being easily and quickly effected. If it is desired to support the globe or shade, after the insertion of its neck portion within the skirt portion 6 and after engagement with the resilient fingers 12 has been effected, the free end portion 19 of the third supporting member 18 is moved by its operating lever inwardly into engagement with the globe neck portion. The globe or shade is therefore yieldingly but firmly 20 supported at three circumferentially spaced points. To remove the globe or shade, it is only necessary to move the supporting member 18 and its operating lever to their dotted line positions, Fig. 2, such movement being 25 effected by simply operating the lever, as will be readily understood.

Due to the fact that the lever head end and handle portions are bent at an angle to each other slightly greater than ninety degrees, 30 the lever head end portion does not extend truly radially into the body member 1 as clearly indicated in Fig. 2. As a consequence, said lever end portion is not pushed outwardly by the resilient supporting member 18 when these interengaging parts are in their globe supporting positions shown in full lines in Fig. 2. If desired, the supporting member 18 may be provided in its free end portion 19 with one or more recesses 24 35 to receive the end of the lever head end portion 22 when in their globe supporting positions.

It is to be noted that the lever head end portion 22 is wider than the lever handle portion 23 and the slot 21 in the skirt portion 6. As a consequence, the lever is prevented from escaping outwardly through said slot, and its escape inwardly is prevented by member 18.

60 In the modified holder illustrated in Figs. 5 to 8 inclusive, the resilient supporting member 18 is dispensed with, and the head end portion 30 of a lever is used to directly engage and support the globe neck portion 65 10. Said lever includes an operating handle

portion 32 and is in most respects identical with the lever used to operate the supporting member 18 of the holder illustrated in Figs. 1 to 4 inclusive. The chief distinction is that the lever handle portion 32 is made substantially as wide as the lever head end portion 30, both portions being of greater width than the height of the lever slot 35 in the skirt portion 6 of the holder body member 1, the height of said slot being substantially the same as the width of the lever neck portion 36 which connects the lever head end and handle portions. In order to permit the lever head end portion 30 to be passed inwardly through the skirt slot 35, said slot is provided at its upper and lower ends with lateral extensions 37, which receive the side parts 38 of the lever head end portion when said parts are bent laterally, as shown in full lines Fig. 8. After the lever head end portion has been passed inwardly through slot 35, the side parts 38 of said lever portion are bent back to their dotted line position, Fig. 8, which effectively confines the lever in proper position in the skirt slot 35.

The use of the supporting member 18 of Figs. 1 to 4 inclusive enables a greater area of the globe neck portion 10 to be engaged, as will be readily understood and as indicated in Fig. 2, but the lever head end portion 30 of Figs. 5 to 8 inclusive engages a sufficient amount of the globe neck to provide and insure a firm support of the globe.

What I claim is:

1. A globe or shade holder, comprising a housing hanger member having a cylindrical skirt portion at its lower end, a pair of circumferentially spaced resilient fingers secured to the inner surface of said skirt portion for supporting engagement with a globe or shade neck, an elongated globe engaging member of resilient form arranged in opposed relation to said globe engaging fingers, said elongated member extending circumferentially of said skirt portion and having one of its end portions secured to the inner surface thereof and its other end portion free for radial movement into and out of globe engaging position, and a lever for actuating the free end portion of said elongated resilient member, said lever being fulcrumed in an opening in said skirt portion and having an arm inside the hanger member for slidably engagement with the free end portion of said elongated member, said lever also having an arm outside of said hanger member for manual operation, said inner and outer lever arms extending at substantially right angles to each other with the outer arm curved to conform to the curvature of the skirt portion of the hanger member, whereby when the inner arm is holding the free end portion of the elongated resilient member inwardly in globe engaging position, the outer lever arm hugs or lies

closely alongside the outer surface of the hanger member skirt portion in an inconspicuous manner.

2. A device as set forth in claim 1 wherein the free end portion of the elongated resilient member is provided with a transverse depression to receive the inner edge of the

inner lever arm when said arm is holding said free end portion inwardly in globe engaging position. ¹⁰

In testimony whereof I hereby affix my signature.

FREDERICK WENING.
